(No Model.)

C. W. MORLEY.
INTERNAL PIPE CUTTER.

No. 595,885.

Patented Dec. 21, 1897.

UNITED STATES PATENT OFFICE.

CHARLES WM. MORLEY, OF LAWTON, MICHIGAN.

INTERNAL PIPE-CUTTER.

SPECIFICATION forming part of Letters Patent No. 595,885, dated December 21, 1897.

Application filed October 14, 1896. Serial No. 608,874. (No model.)

To all whom it may concern:

Be it known that I, CHARLES WM. MORLEY, a citizen of the United States, residing at the village of Lawton, in the county of Van Buren and State of Michigan, have invented 5 a certain new and useful Internal Pipe-Cutter, of which the following is a specification.

My invention relates to improvements in internal pipe-cutters.

10 In the sinking of tubular wells the bottom of the pipe frequently becomes bent or injured by coming in contact with rocks or other obstructions and not infrequently the pipe of an old well becomes lodged in the soil, 15 so that it cannot be removed. The pipe itself is valuable if it could be removed without the expense of digging for it. When the lower end of a pipe becomes injured in sinking a well, it is frequently possible to cut off 20 a few feet of the pipe, raise the whole portion of the pipe away from it, and drop in a dynamite cartridge, which will not only remove the portion of the injured pipe below, but will shatter the obstruction beneath and 25 enable the builder to sink the pipe along the same line and in the language of well-diggers not "lose the hole."

The objects of this invention are, first, to provide an internal pipe-cutter which can be 30 used at any distance from the end of the pipe and be operated safely, successfully, and powerfully; second, to provide an improved and simplified construction of pipe-cutters; third, to provide improved means of feeding the cutting-blades and guiding the same in an internal pipe-cutter, and further objects appearing definitely in the detailed description. I accomplish these objects by the mechanism and means described in the following specification and illustrated in the accompanying drawings, in which—

Figure 1 is a view of a section of pipe broken in sections, in which one of my internal pipe-cutters is in use, a portion of the 45 same being in section 1 on line 1 1 of Fig. 2. Fig. 2 is an enlarged detail sectional view on line 2 2 of Fig. 1. Fig. 3 is an enlarged detail sectional view on line 3 3 of Fig. 1. Fig. 4 is an enlarged detailed vertical sectional 50 view on line 4 4 of Fig. 2. Fig. 5 is an enlarged detail sectional view on line 5 5 of Fig. 1.

In the drawings all of the sectional views are taken looking in the direction of the little arrows at the ends of the section-lines.

55

Similar letters of reference refer to similar parts throughout the several views.

Referring to the lettered parts of the drawings, A represents the pipe that is to be cut, which, for consistency in description, I will 60 call a "well-pipe."

B' is the main block or shell of the pipe-cutter, cylindrical in form, and is secured to the bottom end of the pipe B, which extends inside of the well-pipe A. The block B' is of 65 the size to fit loosely the interior of the well-pipe A. On the bottom of the pipe B' is a cutter plate or blade D and a guide plate or blade D', which are supported in suitable guideways at the bottom of block B', which 70 is preferably in separate plates G G, that being the most convenient way of making the same. That structure possesses considerable merit on account of its simplicity and ease of construction. Through the inner end of the 75 plates B' are mortised dovetail apertures a', which serve as a retaining means for the plates D D'. Down through the cylinder B' are openings e e, which come opposite the outer end of the blades D D' and serve to deliver oil to the same, slight openings being 80 extended out over the tops of the blades through to their ends. The wedge-shaped piece C' is secured to the bottom end of the rod C, which projects up through a small pipe 85 B and out of the top of the same. The top terminates in a small screw, on which is a hand-wheel F, which is threaded at the center. The hand-wheel rests against the top of the pipe B. Toward the top end of the pipe 90 B is fixed a collar B'', that rests on the top of the pipe A. The collar is operated by a wrench E, which is preferably a ratchet-wrench.

The pipe B and the rod C are conveniently 95 adjustable to any desired length by making the same jointed, so that the lengths can be removed or added thereto.

Having thus described and enumerated the parts of my improved pipe-cutter, I will now 100 point out the method of its use.

When it becomes necessary to cut off a length of pipe, the block B', with the blades D D' thereon, is inserted to the required level.

or distance and lengths of the pipe B and rods C are added until the same project above or beyond the well-pipe A. The collar B" is then secured to the pipe B and the hand-wheel 5 F is turned onto the rod C. Oil of course is placed in the openings e e at the beginning. The pipe and the block B' below of course being connected both are revolved by means of a wrench E acting on the collar B". As 10 the same is turned around the blade D is fed outwardly against the interior of the tube A by turning the hand-wheel, which draws up the rod C and consequently the block C', which is attached thereto. This feeds the 15 cutter-blade outwardly in one direction and the guide-plate D' in the opposite direction, and as the whole is continued to be turned by the wrench cuts the pipe below from the interior. When the pipe has been severed, 20 the hand-wheel F is turned in the opposite direction, the wedge descends, and by its engagements with the inner ends of the plates D D' withdraws the same, so that the entire 25 tool and apparatus can be lifted from the inside of the pipe.

Having thus described my new and improved internal pipe-cutter, I desire to state that it can be considerably varied in its details without departing from my invention.

30 In the place of the hand-wheel F a nut and a wrench might be used. Other attachments than the ratchet-wrench might be provided for rotating the collar B".

I also desire to say that different blocks B' 35 could be provided with different sets of knives to cut different-sized pipes. Blades D, with different-shaped cutting edges, might be provided for various purposes, such as smoothing portions of the interior of the pipe or 40 reaming out joints where such may be required.

I also desire to state that my improved internal pipe-cutter is desirable for use in cutting pipe above ground and leaves it much

smoother cut on the pipe than the usual external cutter. 45

Having thus described my invention, what I claim as new, and desire to secure by Letters Patent, is—

1. In an internal pipe-cutter, the combination of the cylindrical block B', guide plate or blade D', and cutting plate or blade D, supported by suitable guide-plates G, G, at the bottom of said cylinder B', the said cylinder containing oil-holes e, e, therethrough, 55 extending out over the blades to the edge thereof; a suitable pipe B, attached to said block B', and extending to the end of the pipe; a collar B", on the end of the pipe B, to rest against the end of the pipe to be cut; a 60 wedge-shaped block C', pointing upwardly into the bottom of the cylindrical block B', having dovetails or ridges a, a, which engage in corresponding slots on the inner ends of the blades D, D'; a rod C, secured to wedge-shaped piece C', and extending upwardly through the pipe B, and terminating in a screw at the top; and a hand-wheel F, screw-threaded to fit against the top or outer end of the pipe B, all coacting together substantially as 65 described for the purpose specified. 70

2. In an internal pipe-cutter, the combination of a cylindrical block B', adapted to fit within a pipe; having suitable guideways on its lower end to receive the cutter-blades and 75 having oil-receptacles formed within it with grooves leading along the guideways for the cutter-blades; cutter and guide blades within the guideways at the bottom of said block so positioned that the oil from the receptacles 80 in the block can pass out upon the same to lubricate them for the purpose specified.

In witness whereof I have hereunto set my hand and seal in the presence of two witnesses.

CHARLES WM. MORLEY. [L. S.]

Witnesses:

JUAN MCKEYES,
F. H. MCKEYES.
